UNITED STATES PATENT OFFICE.

JOHN S. BOYD AND THOMAS F. BOYD, OF WILLIAMSTOWN, MASSACHUSETTS, ASSIGNORS TO JOHN S. BOYD CO. INC., OF WILLIAMSTOWN, MASSACHUSETTS, A CORPORATION OF MASSACHUSETTS.

DESIGN FOR A TEXTILE FABRIC.

Application filed December 12, 1922. Serial No. 4,573. Term of patent 14 years.

To all whom it may concern:

Be it known that we, JOHN S. BOYD and THOMAS F. BOYD, citizens of the United States, residing at Williamstown, county of Berkshire, and State of Massachusetts, have invented a new, original, and ornamental Design for Textile Fabrics, of which the following is a specification, reference being had to the accompanying drawing, forming a part hereof.

The figure shown is a plan view of a section of textile fabric, showing our new design.

We claim:—

The ornamental design for a textile fabric as shown.

JOHN S. BOYD.
THOS. F. BOYD.
